EDWARD E. STANLEY, OF EMMETT, IDAHO, ASSIGNOR, BY MESNE ASSIGNMENTS, TO
CHESTER F. STUDLEY, OF SONOMA, CALIFORNIA.

RAISIN STEMMER.

1,411,528.

Specification of Letters Patent. Patented Apr. 4, 1922.

Application filed April 26, 1921. Serial No. 464,588.

To all whom it may concern:

Be it known that I, EDWARD E. STANLEY, a citizen of the United States, residing at Emmett, in the county of Gem and State of Idaho, have invented certain new and useful Improvements in Raisin Stemmers, of which the following is a specification.

My invention relates to that class of raisin-stemmers in which the fruit, after subjection to the stem-detaching effect of a coating cylinder and concave is, together with the detached stems, advanced into the sphere of action of a blast of air to blow the stems from the raisins.

In machines of this type, the endeavor has been to present the advancing mass or aggregate of raisins and detached stems, in a layer-like form, to the action of the air blast whereby a separation is effected according to their different coefficients of gravity; but owing partly to the nature of the fruit, and partly to the restricted zone of application of the blast, the best results have not been attained, it being found in practice that the agitation of the mass, due only to the mechanical shaking of the advancing table, is not sufficient to place the layer, with respect to the relative positions of its components, in such condition as to cause the air blast to act distinctively upon the lighter particles. The consequence is that, due to the insufficient spreading out of the mass, and the complete intermixture of its components, many of the raisins are blown over with the stems, thereby requiring re-running and subsequent manipulation.

The object of my invention is to produce a more complete separation of the raisins and detached stems and other foreign particles, and this I attain by a more efficient spreading of the mass into a relatively thin layer, and its subjection in successive zones first to an air blast of relatively low velocity sufficient only to move the lighter particles to the top of the layer, and, second, to an air blast of higher velocity sufficient to carry off the overlying lighter particles without materially affecting the heavier ones.

With this object in view, my invention consists in the novel raisin-stemmer which I shall now fully describe by reference to the accompanying drawings, in which—

Fig. 1 is a top plan view, broken, of my machine.

Fig. 2 is a section on the line 2—2 of Fig. 1.

Fig. 3 is a detail plan view, enlarged and broken, of a portion of the perforate section of the table 5.

Fig. 4 is a section on the line 4—4 of Fig. 3.

Fig. 5 is a section on the line 5—5 of Fig. 2.

Fig. 6 is a longitudinal section of the blower on the line 6—6 of Fig. 2.

1 indicates parts of the general frame of the machine. 2 is the rotatable stemming cylinder and 3 is the stationary concave, both cylinder and concave being of the usual construction with wire-mesh surfaces as indicated. 4 indicates a feed guide to supply the raisins to the space between the cylinder and concave, through which said space they are carried by the rotation of the cylinder, and their stems detached by friction. In machines of this type, it is usual to break up the clusters and tear off many of the cluster stems by suitable means operating in advance of the cylinder, so that in the concave, the stems detached are chiefly the small or "cap" stems, though, of course, any undetached larger stems or broken portions thereof will also be torn off.

The cylinder discharges the aggregate material composed of the fruit, the detached and broken up stems of all kinds, and foreign particles, dust, chaff, sand, etc. directly upon the receiving end of a table 5, suitably mounted for vibration, as, for example, on a swinging link 7", Fig. 2; said table having a vibrating motion, in the direction of its length, imparted to it by suitable means, as, for example, by the eccentric 7 and connecting rod 7', as shown in Fig. 2. The table 5, according to my invention, has several distinctive or novel peculiarities. One is its superficial shape, which as seen in Figs. 1 and 5 consists in its widening out or flaring fan-like, from its receiving end. The table is bordered by side flanges 5', and its surface is preferably, though not essentially, provided with diverging guide cleats 5", to better effect the equal distribution and spreading out of the mass of material passing over it, as indicated by the arrows in Fig. 1. Another feature of the table 5 is the division of its surface into transverse zones or sections, the first of which, nearest

the cylinder, and indicated by 5^a is imperforate, the second indicated by 5^b is perforate, and the third shown at 5^c is a grating composed of parallel spaced fingers.

5 The perforated zone or section may be of any character, as, for example, screen-like of a wire-mesh nature or a punched plate, but the form I prefer, on account of the function I wish it to have, I show particularly in Figs. 3 and 4. In this form the table section 5^b is punched with a plurality of narrow crescent slits, the concave sides of which face the cylinder, with the shorter walls slightly elevated, as in Fig. 4.

10 15 6 is an air blower, located below the table 5. This blower, though it may be of any character, is, in its preferred form, as shown in Fig. 6, composed of a pair of encased aligned and spaced fan rotors 8, each adapted to take in air from each end, and having inclined vanes 8' so arranged that the air taken in will be directed centrally in each rotor and thus equally distributed in volume, throughout the length of the blower.

20 25 15 The discharge aperture 6' of the blower (Fig. 2) which as seen in Fig. 5 extends the full length of the blower casing, communicates with a double delivery passage. One of these, indicated by 9 and which is defined by walls 9' widens out to include at its upper extremity, the whole area of the perforate zone or section 5^b of the table, under which it lies. See Fig. 2.

30 35 15 The other delivery passage of the blower is the wind-trunk 10 which, at its upper end, opens out below and includes in its sphere of action the grate-section 5^c of the table 5, Fig. 2.

40 A valve flap 10' controls the relative volumes of air permitted in the passages 9 and 10.

11 45 15 11 is a baffle-board beyond the table 5. This board is hinged at 11', Fig. 2, for adjustment as required.

12 50 15 12 is a hood over the sections 5^b and 5^c of table 5.

13 55 15 13 is a receiver for the raisins, from which they may be carried by suitable means to their destination.

50 60 15 The operation of the machine is as follows.

65 The material having been, as previously stated, subjected to the stem-detaching action of the cylinder and concave, is delivered upon the imperforate section 5^a of the shaking table 5. Upon this table, due to its movement and its flaring shape, the material at once begins to advance and gradually to spread out into a relatively thin layer, the 60 guide cleats 5" assisting in this effect, and giving an equal distribution. The shaking of the table tends to lighten up the mass, but not sufficiently to materially alter the positional relation of its components; but as it 65 reaches the perforate section or zone 5^b of the

table, it encounters the current of air rising through said section from the air passage 9. This current, due to its relatively extensive delivery is of low velocity, insufficient to blow the raisins off, but ample to so agitate 70 the mass and lighten it up as to float, as it were, the lighter components, namely, the stems, dust, chaff, etc. to the top of the layer and keep them there. In this condition the material then reaches the grate-section 5^c 75 of the table, and here meeting with the air current of greater velocity from the wind trunk 10, the stems and foreign particles are blown away over the baffle board 11, while the raisins drop from the table into 80 the receiver 13.

85 Sand and other relatively heavy small foreign particles, which may be in the material, are not likely, no matter what may be the special character of the perforated section 85 of the table, to drop through into the wind passage, as the air current will prevent this; but with the special form of perforations which I prefer and herein show, such particles will ride up on and over the elevated 90 walls of the narrow slits, and will be carried thereover by their momentum and by the air current and will not fall through.

I claim:—

1. In a raisin-stemmer, the combination of 95 a table to which an aggregate of raisins and their detached stems is fed and upon which it is advanced, said table being pervious to air; means for directing a current of air from below, through said table, upon said 100 aggregate advancing thereon said air-current having velocity, adapted to loosen up the mass and carry the stems to the top; and means for directing another current of air from below through said table upon said 105 mass in a region beyond the sphere of the first current of air and of relatively higher velocity, adapted to blow said stems away from the raisins.

2. In a raisin-stemmer, the combination of 110 a table to which an aggregate of raisins and their detached stems is fed and upon which it is advanced, said table being pervious to air, and from its receiving end flaring to a wider width in the direction of its discharge 115 end; means for directing a current of air from below, through said table, upon said aggregate advancing thereon said air current having velocity, adapted to loosen up the mass and carry the stems to the top; and 120 means for directing another current of air from below through said table upon said mass in a region beyond the sphere of the first current of air and of relatively higher velocity, adapted to blow said stems away 125 from the raisins.

3. In a raisin-stemmer, the combination of 130 a table to which an aggregate of raisins and their detached stems is fed and upon which it is advanced, said table being pervious to

- air, and from its receiving end flaring to a wider width in the direction of its discharge end; divergent guide cleats on the flaring table; means for directing a current 5 of air from below, through said table, upon said aggregate advancing thereon said air-current having velocity, adapted to loosen up the mass and carry the stems to the top; and means for directing another current of 10 air from below through said table upon said mass in a region beyond the sphere of the first current of air and of relatively higher velocity, adapted to blow said stems away from the raisins.
- 15 4. In a raisin-stemmer, the combination of a table to which an aggregate of raisins and their detached stems is fed and upon which it is advanced, said table having at its receiving end an imperforate section, a per- 20 forate section following said imperforate section, and a grate section comprising its discharge end, said table flaring in width from its receiving end to its perforate section; means for directing a current of air 25 from below through the perforate section of the table said air-current having velocity, adapted to loosen up the mass passing there-
- over and carry the stems to the top; and means for directing another current of air of relatively higher velocity from below 30 through the grate-section of the table, adapted to blow said stems away from the raisins.
5. In a raisin-stemmer, the combination of a table to which an aggregate of raisins and their detached stems is fed and upon which 35 it is advanced, said table having a grate-section comprising its discharge end, and a section in advance of said end which is perforated with narrow slits, the edges of which, lying nearer the receiving end of the 40 table, are slightly elevated above the table surface; means for directing a current of air from below through said narrow slits of the perforate section of the table said air-current having velocity, adapted to loosen 45 up the mass passing thereover and carry the stems to the top; and means for directing another current of air of relatively higher velocity from below through the grate section of the table, adapted to blow the stems 50 away from the raisins.

In testimony whereof I have signed my name to this specification.

EDWARD E. STANLEY.
